L. Lewis

Cotton Press.

N° 9,197.

Patented Aug. 17, 1852.

UNITED STATES PATENT OFFICE.

LEWIS LEWIS, OF VICKSBURG, MISSISSIPPI.

IMPROVEMENT IN COTTON-PRESSES.

Specification forming part of Letters Patent No. 9,197, dated August 17, 1852.

To all whom it may concern:

Be it known that I, LEWIS LEWIS, a citizen of the United States, and residing at Vicksburg, in the county of Warren and State of Mississippi, have invented a new and useful Improvement in Cotton, Hay, Hemp, and Tobacco Presses, and also the same principle when applied to presses of different sizes and for other purposes; and I do hereby declare that the following is a description of the construction, application, and operation of the same by Figures 1 and 2.

Fig. 2 represents the frame that holds the press to its place at the top. The cross-beam (marked B) on the top of the screw, being forked at each end, moves up and down the posts numbered 2 and 2, as the case may require, and keeps the screw from revolving. Figs. 3 and 3 and 4 and 4 represent the floor of the house in which it may stand; B, the cross-beam on the top of the screw; D, the small ends; E, the upper female; F, the sliding nut; G, the follower; K K, the stems of the follower connected to the sliding nut; I and L, the pieces that the box-plank is fastened to; R and Q, the top and bottom of the box; S, the bale; I, the bed-piece of the press; K and K, the gullens; M, the doors of the press; O, the blocks that support the weight of the press on the ground; P, the gudgeon that the press revolves on, the press standing perpendicular, and revolves around the screw, turning on the gudgeon P. The drawings No. 1 on file repre-

sent a side view of the press partly run up, which is referred to as part of this description.

My press works with great ease and convenience. The upper end rising faster than the lower end, takes the point of the screw out of the way of the hands engaged in filling cotton, hay, &c., and the different size of the screw at each end strengthens the screw in the center where it most needs strength, and it also works with greater power. There is a groove in each end of the nut to keep it permanent, and makes it revolve around the screw with the balance of the press, at the same time facilitating the speed near one-half.

Having thus fully described the nature and operation of my press, what I claim therein as of my invention and desire to secure by Letters Patent is—

The arrangement of the press hereinabove described in such manner that it may be conveniently charged in an upper story of the building in which it is placed, and actuated and discharged in a lower story of the same, substantially as herein set forth, reference being had in my claims for Letters Patent to the drawings and specifications as filed and hereinbefore set forth.

LEWIS LEWIS.
